CLAIM

The ornamental design for a perfusion module lid without ports, as shown and described.

DESCRIPTION

FIG. 1 is a top plan view of an ornamental perfusion module lid without ports.

FIG. 2, is a bottom plan view, thereof.

FIG. 3 is a left side elevational view, thereof.

FIG. 4 is a right side elevational view, thereof.

FIG. 5 is a front side elevational view, thereof.

FIG. 6 is a rear side elevational view, thereof; and,

FIG. 7 is a top elevational view, thereof.

The broken lines in the drawings depict features of the perfusion module lid without ports that do not form part of the claimed design.
